UNITED STATES PATENT OFFICE.

ARTHUR A. BYERLEIN, OF DETROIT, MICHIGAN.

POWER-PRESS CONTROL.

Application filed January 7, 1925. Serial No. 1,018.

The present invention relates to power presses of the type adapted for use in stamping metal, and particularly to the control means therefor.

5 One of the principal objects of the present invention is to provide such a power press with clutch operating means so constructed that the press may be stopped either automatically at a predetermined period in the 10 operation of the press or manually controlled at any time as desired.

A further object is the provision of a 15 control mechanism for presses and machines of like character having means operating automatically to stop the press, in which initial movement of a control member by which the press is manually controlled is operable to disconnect the engagement of such automatic stopping means.

20 Other objects and advantages of the invention will be apparent from the following description taken in connection with the accompanying drawings, in which—

Fig. 1 is a front elevation of a portion 25 of the press showing the control mechanism;

Fig. 2 is a side elevation of the press;

Fig. 3 is an elevation of the trip mechanism forming part of the present invention;

30 Figs. 4 and 5 are sectional views, with parts broken away, taken on the line 4—4 of Fig. 3 and showing several operating positions of the trip mechanism;

Figs. 6 and 7 are views similar to Figs. 4 35 and 5, showing a second form of the trip mechanism;

Fig. 8 is an exploded sectional view on the line 8—8 of Fig. 6;

Fig. 9 is a side elevation of a third form 40 of trip mechanism;

Fig. 10 is a sectional view of Fig. 9 corresponding to Fig. 4; and

Fig. 11 is a detail view of the trip actuated member.

45 Referring to the drawings, and particularly Figs. 1 to 5 showing one form of the invention, 20 designates a power press only part of which is shown. This press is provided with a slide member 21 slidably mounted in the side frame 22 and driven from the crank shaft 23. The slide 21 may be connected to the crank shaft 23 by cranks 19 or any other suitable means which will impart to the slide 21 a reciprocating motion upon rotation of the crank shaft 23 in one direction.

In presses used for stamping metal the

slide is generally operated intermittently, one complete cycle of operation consisting of a forward or down stroke of the slide 21 followed by a backward or up stroke of the 60 slide 21, the slide being brought to rest in an upper position to permit of removing the formed work and inserting a fresh blank. For the purpose of imparting intermittent motion to the slide, the press is 65 provided with a continuously rotating shaft 24 to which the crank shaft may be connected from time to time by means of a gear train including the gear 25 and a clutch 26. In the form of clutch herein shown the outer 70 shell or casing is adapted to rotate when the crank shaft 23 is being driven from the shaft 24, and to assist in arresting the crank shaft 23 and clutch 26 at the proper point, the press may be provided with a brake band 75 27 which is adapted to bear frictionally upon the outer surface of the clutch housing or casing 26.

The clutch and the brake are controlled from the clutch control shaft 30 to which is 80 keyed a lever 31, the lower portion of which is formed as a yoke and is connected with clutch sleeve 32. The upper end of the lever 31 is connected through link 33 to the joint between toggle links 34 and 34', link 34' 85 being pivoted at its lower end to a fixed axis so that movement of link 33 rocks the arm 35 to which the upper toggle lever 34 is pivoted. Arm 35 is fast on a rock shaft which bears a second arm 35' connected at its end 90 to rod 36' which is fastened at one end of the brake band 27, the opposite end of which is fastened at 37' as shown in Fig. 2. The construction of the clutch is such that when the clutch operating lever 31 is turned in a 95 clockwise direction, as viewed in Fig. 1, the clutch connects the crank shaft 23 with the shaft 24 to cause operation of the press. At the same time the lever 31 breaks the toggle 34 to release the brake 27 as will be apparent 100 from Fig. 1. When the shaft 30 is rotated in an opposite or counter-clockwise direction the operation of the clutch and the brake is reversed, that is, clutch collar 32 is moved to the right to disengage the clutch and at 105 the same time the toggle 34 is actuated to apply the brake 27. While the brake is, broadly speaking, released while the clutch is engaged and is applied while the clutch is disengaged, it should be understood that 110 the exact time of application or release of the brake 27 with respect to the operation

of the clutch may be varied within wide limits, depending upon the adjustment of the clutch and the brake and its operating mechanism.

5 The operation of the clutch and brake to thereby effect connection or disconnection of the slide 21 and the crank shaft 23 may be controlled by a control mechanism consisting of certain linkage and trip mechanism which will now be described. The control mechanism consists, broadly speaking, of an operating handle 40 which when moved to the press starting position 40^a as shown in dotted lines in Fig. 1, moves the link 41 upwardly which movement is transmitted through the operating shaft 42 to raise the link 43 thereby causing engagement of the clutch and release of the brake and consequent operation of the press. The press 10 may be stopped at any point in its cycle of operation by returning the operating handle 40 manually to its original position or it may be stopped automatically by trip mechanism connected direct with the crank 15 shaft 23 by means of a link 44.

20 Referring particularly to Figs. 3, 4 and 5, the control mechanism includes an operating shaft 42 journaled for rotation in a bracket 46 secured to the side frame of the press. Link 43 is connected between a rearwardly extending lever 47 rigidly secured to one end of the shaft 42 and a rearwardly extending lever 36 is rigidly secured on the clutch operating shaft 30. A trip pawl lever 48 is non-rotatably keyed to the shaft 42. This lever is U-shaped as shown in Fig. 11, the cross bar of the U being a forwardly extending or head portion 49 and the arms being a pair of spaced apart rearwardly extending arms terminating in lugs 50. Loosely mounted on the operating shaft 42 between the lugs or arms 50 of the U-shaped trip pawl lever is a lever 51 which has lugs 52 and 53 extending from opposite sides thereof for engagement with the lugs 50 of the trip pawl lever 48. The lugs 52 and 53 are so spaced as to permit a certain amount of lost motion between themselves and the lug 50 for a purpose to be hereinafter explained. 25 The lever 51 is pivotally connected with the upper end of the link 41, the lower end of which link is connected to a lever 54 rigidly secured to one end of the shaft 55 upon which is carried the operating handle 40. A weighted lever 56 is also secured on the shaft 55 to bias this shaft and the operating handle 40 towards the right or press stopping position as viewed in Fig. 1, and consequently tend to maintain it in its normal relationship with operating shaft 42, with the lug 52 engaging the lug 50 fast on the shaft.

30 Loosely mounted on the operating shaft 42 on either side of the trip pawl lever 48 are a pair of triangular frames 57 which

are connected by bolts and spacers as at 59 and 60 to form a cage-like carrier, which will be herein termed the trip pawl carrier. Pivotally mounted on bolt 60 of the trip pawl carrier is an actuating part or trip pawl 61 having a notch or shoulder 62 adapted to engage a face or shoulder 63 formed on the forwardly extending portion 49 of trip pawl lever or actuated part 48. The trip pawl or actuating part 61 is normally held in engagement with the actuating part of trip pawl lever 48 by means of a spring pressed plunger 64 which is carried in boss 65 of the trip pawl carrier. The portion 49 of the trip pawl lever 48 carries an unlocking pin 66 slidably mounted in an aperture extending through the lug 49 from front to rear, the forward end of the unlocking pin 66 being in line with a portion of the trip pawl or actuating part 61 and the rearward end of the unlocking pin being in line with an upwardly extending unlocking lug 67 formed on the lever 51. Unlocking pin 66 is yieldingly held in its rearward position as indicated in Fig. 4 by a spring or other suitable means. The trip pawl carrier is connected by means of bolt 59 and link 44 with a crank plate 68 secured on the end of crank shaft 23. This crank plate 68 is angularly adjustable with respect to the end of the crank shaft 23, by means of the slots and locking bolts shown in Fig. 2, whereby the position of the trip pawl carrier and link 44 may be varied with respect to the stroke of the slide 21.

35 To place the press in operation the operating handle 40 is moved to the press starting position 40^a as indicated in dotted lines in Fig. 1. This raises the link 41 and lever 51, whereupon the lug 67 carried by the lever 51 moves the unlocking pin 66 to the right, from the position in Fig. 4, to disengage the trip pawl 61 from the lip or shoulder 63 of the trip pawl lever or actuated part, as shown in Fig. 5. On further travel of the lever 51, 40 after the trip pawl lever 61 has been thus disengaged, the lugs 53 engage the lugs 50 to rock the operating shaft 42 in a clockwise direction to the position shown in Fig. 5. The link 43 is thus moved upwardly to cause 45 engagement of the clutch 26 thereby placing the press in operation. Rotation of the crank shaft 23 of course rotates the crank plate 68 which is mounted on the crank shaft 23, so that, coincidently with the downward movement of slide 21, the link 44 moves downwardly and swings the trip pawl carrier to the position indicated in dotted lines in Fig. 5, in which position, it will be observed, there is a considerable clearance between the lip or shoulder 62 of the trip or actuating part and the lip or shoulder 63 of the actuated part 48. During the upward movement of the crank plate 68 and slide 21 the trip pawl carrier again swings upwardly 50

carrying with it the trip pawl or actuating part 61, and during the latter part of this upward movement shoulder 62 of the trip pawl engages shoulder 63 of the trip pawl lever or actuated part and returns the latter to its initial position as shown in Fig. 4, thereby disengaging the clutch and stopping the press. In this connection, it should be noted that immediately upon the release of the operating handle 40 by the operator, the lever 51 swings downwardly under the influence of the weight 56 until the lugs 52 are in engagement with the lugs 50, and the lug 67 on the lever 51 is withdrawn from engagement with the unlocking pin 66, thereby permitting the latter to return to its initial position. But the effect of the weight 56 is not sufficient to move the control mechanism to disengage the clutch, although it does swing the lever 51 upon the shaft 42 to withdraw the unlocking pin 66 so that all obstacles to the engagement of the lips or shoulders 62 and 63 on the upward movement of the pawl 61 are removed, and the pawl 61 therefore engages the trip pawl lever 48 to stop the press, as already explained.

From the foregoing, it will be apparent that the present invention provides means for manually starting the press and automatically stopping it. It will be perceived also that since operating handle 40 is permanently connected with clutch 26 and brake 27 through link 41, lever 51, operating shaft 42, and link 43, the press may be stopped at any time by simply moving the operating handle 40 from the dotted line position 40^a all the way to the full line position 40 shown in Fig. 1; and likewise, because of this permanent connection, the press may be restarted from any position in which it has been stopped. Should it be desired to disable or render inoperative the automatic stopping mechanism so that the press will operate continuously, subject only to manual control by the operating handle 40, this may be done by locking the trip pawl 61 in raised position whereby it can not engage the shoulder 63 of the trip pawl lever. To lock the trip pawl in raised position the trip pawl carrier is provided with a locking pin 69 (see Fig. 3) which may be turned and permitted to drop, under the action of a suitable spring, into a hole or depression 70 formed in the side of the trip pawl 61. Handle 71 is provided for convenience in lifting the trip pawl 61 to lock the same in raised position.

In the form of tripping mechanism shown in Figs. 4 and 5, it will be observed that should the operator hold the operating lever in the starting position 40^a for a sufficient length of time after the press has been placed in operation, then the unlocking pin 66 will be held in its forward or unlocking position as shown in Fig. 5, so that the shoulder 62 of the trip pawl 61 will be prevented from

engaging the shoulder 63 of the trip pawl lever so that the press will not be automatically stopped and as a consequence the slide 21 of the press will continue to operate instead of coming to rest at the top of its stroke 70 as previously described, so long as the handle is thus held.

Figs. 6, 7 and 8 illustrate a second form of the tripping mechanism in which there is provision for preventing such continued operation of the slide member 21 as a result of the operator holding the operating handle 40 in the starting position 40^a. In this form of the tripping mechanism which forms the subject matter of a divisional application filed June 11, 1927, Serial No. 198,297, and entitled "Power press control," and which is generally similar in its general arrangement of parts and in its operation to the form of the invention shown in Figs. 1 to 5, the unlocking pin 166 is permanently connected by means of a pivoted link 190 with the lug 167 carried by the lever 51. The trip pawl or actuating part 161 is pivoted at 60 to the trip pawl carrier 57 and carries at its upper end a pair of grooved side plates 191 which provide a guide for a slidable trip pawl block 192 having a head portion and a depending slide portion. A screw 193 secured in the trip pawl 161 and passing through an aperture in the trip pawl block 192, limits the upward sliding movement of the trip pawl block and at the same time serves as a central supporting post for coiled spring 194 which spring holds the trip pawl block in its uppermost position. Downward sliding movement of the trip pawl block 192 is limited by engagement of the block itself with the end of the trip pawl 161 as illustrated in Fig. 7. A pair of lips or shoulders 162 extend laterally from the side plates 191 for engagement with the lip or shoulder 63 of the trip pawl lever 48.

To start a press having a control mechanism embodying the form of tripping mechanism illustrated in Figs. 6, 7 and 8, the operating handle 40 is moved to the starting position 40^a, as illustrated in Fig. 1, in the same manner as already described. This movement by the operator raises the lever 51 and results, first in moving the unlocking pin 166 forward to disengage the trip pawl 161, and second in rotating the trip pawl lever 48 and the operating shaft 42 to the position illustrated in Fig. 7, and to thereby engage the clutch and disengage the brake to place the press in operation. If now the operator holds the operating lever in the starting position 40^a shown in Fig. 1, the tripping mechanism will be held in the position illustrated in Fig. 7. With the placing of the press into operation, the trip pawl carrier 57 and trip pawl 161 will, of course, swing downwardly as already described, and upon its upward movement the lip or

shoulder formed by the upper surface of the sliding pawl block 192 will engage the unlocking pin 166, which pin is still being held in its forward or unlocking position. However, owing to the sliding and yielding support of the trip pawl block 192, the latter slides downwardly and permits the shoulder 162 of the trip pawl 161 to engage and actuate the shoulder 63 of the trip pawl lever or actuated part 48, thereby rocking the trip pawl lever in a counter-clockwise direction to stop the press, at the same time forcibly moving the lever 40 to inoperative position.

From the foregoing it will be perceived that with this form of tripping mechanism, it is impossible for the operator to maintain the press in continuous operation merely by holding the operating handle in the starting position. The press may, however, be placed in continuous operation by the provision of such means as already described for holding the trip pawl in an elevated or nontripping position; and it may also be started or stopped manually at any desired period in the operation of the press, in the same manner as the form of the invention shown in Figs. 1 to 5, merely by suitable movements of the operating handle 40.

Figs. 9 and 10 show a third form of tripping mechanism which operates in the same general manner as the mechanism already described but in which the tripping mechanism, consisting of the trip pawl 80, trip pawl carrier 81, and trip pawl lever 82, is of slightly different construction. Here the trip pawl 80 is provided with a hook-like shoulder 83 for engagement with the trip pawl lever 82 so that on its upward movement the trip pawl pulls the trip pawl lever 82 upwardly, as distinguished from the construction previously described in which the trip pawl 61 pushes the trip pawl lever upwardly. With this form of tripping mechanism, the operation is substantially the same as with the form of tripping mechanism disclosed in Figs. 1 to 5, that is, the press may be started or stopped manually at any time by suitable movements of the operating handle 40, it may be stopped automatically at the end of each cycle by the rotation of the crank shaft 23, it may be operated continuously by holding the operating handle in the starting position 40^a, or it may be operated continuously upon locking the pawl 80 in the raised or non-tripping position shown in Fig. 9 by means of a locking pin 69^a similar to the locking pin 69, already described.

While the forms of apparatus herein described constitute preferred embodiments of the invention, it is to be understood that the invention is not limited to these precise forms of apparatus, and that changes may be made in either without departing from the scope of the invention which is defined in the appended claims.

What is claimed is:

1. In a power press, a slide member mounted for reciprocation therein, a driving member, a driving connection including clutch means operable when engaged to operatively connect said members and releasable to disconnect said members, manual means including an operating lever and a control member connected thereto through a lost motion for engaging said clutch means to set the press in motion, and means responsive to the movement of the press for automatically disengaging said clutch means to stop the press, said manual means having automatic provisions responsive to the position of said operating lever so as to be operated upon relative movement of said operating lever and control member for rendering said last-mentioned means ineffective to stop the press. 85

2. In a power press, a slide member mounted for reciprocation therein, a driving member, a driving connection including clutch means operable when engaged to operatively connect said members and releasable to disconnect said members, control means including a member manually movable from an initial position to a starting position to cause engagement of said clutch means and consequent operation of the press, and means responsive to the operation of the press for automatically disengaging said clutch means and returning said manually movable member to its initial position, said control means having provisions operable upon the interposition of resistance to return movement of the manually movable member for temporarily disconnecting said automatic means to render it ineffective. 100

3. In a power press, a driving shaft, a slide member adapted to be connected with said driving shaft and to be driven thereby, and mechanism for controlling the connection of the slide member with the driving shaft, said mechanism comprising a member adapted upon movement into starting position to operatively connect the slide member with the driving shaft and upon movement to a stopping position to disconnect the slide member from the driving shaft, a manually controlled lever for moving said member to starting position whereby to operatively connect the slide member with the driving shaft, and automatic means operating upon a predetermined movement of the slide member for moving said member and said manually controlled lever to a stopping position, said mechanism having provisions controlled by the position of the manually controlled lever so as to be operated by initial movement of said lever for temporarily rendering the automatic means ineffective to move said member to stopping position. 115

4. In a power press, a driving shaft, a slide member adapted to be connected with 130

5 said driving shaft and to be driven thereby, and mechanism for controlling the connection of the slide member with the driving shaft comprising a rock shaft adapted to be moved into starting position to operably connect the slide member with the driving shaft and to be moved to a stopping position to disconnect the slide member from the driving shaft, a hand lever manually operable at any time for controlling said rock shaft and connected to said rock shaft through a lost motion, automatic means responsive to the movement of the slide member for engaging and moving said rock shaft 10 15 and hand lever towards starting position, and means operable by the initial starting movement of said hand lever for releasing the engagement of said automatic means and rock shaft to permit the starting of the 20 press.

5. In a power press, a driving shaft, a slide member adapted to be connected with said driving shaft and to be driven thereby, and mechanism for controlling the connection 25 of the slide member with the driving shaft comprising a rock shaft adapted to be moved into starting position to operably connect the slide member with the driving shaft and to be moved to a stopping position 30 to disconnect the slide member from the driving shaft, a hand lever manually operable at any time for controlling said rock shaft and connected to said rock shaft through a lost motion, automatic means responsive 35 to the movement of the slide member for engaging and moving said rock shaft to stopping position, means operated by the initial starting movement of said hand lever for rendering said automatic means ineffective 40 and arranged to permit the continued operation of the press as long as the hand lever is held in the starting position, and means for returning said lever to a normal position in relation to said rock shaft when 45 the lever is released to permit the automatic stopping of the press.

6. In a power press, a driving shaft, a slide member adapted to be connected with said driving shaft and to be driven thereby, 50 brake means for stopping the movement of said slide member, and mechanism for controlling the connection of the slide member with the driving shaft and for operating said brake, said mechanism comprising a 55 rock member adapted upon movement into starting position to operatively connect the slide member with the driving shaft and to disconnect the brake, a control lever connected to said rock member through a lost motion, means normally urging said control lever towards a normal position in relation to said rock member, and automatic means 60 oscillatably mounted and responsive to movements of said slide member for engaging said rock member and moving said 65

mechanism to stopping position to thereby apply the brake and release the clutch, said mechanism having provision operable upon relative movement of said control lever and rock member upon initial starting movement 70 of said control lever for releasing the engagement between said automatic means and said rock member.

7. In a power press, a driving member, a crank-shaft, a clutch between said driving member and crank-shaft, a brake connected to stop the rotation of the crank-shaft, a rock shaft connected to the clutch and to the brake, manual control mechanism capable of manual operation at any time in the operation of the press to effect the manual starting or stopping of the press comprising a control lever and an intermediate control member fast on said shaft and connected through a lost motion to the control 75 80 85 lever, a crank pin mounted eccentrically from said crank-shaft axis, a rod operated thereby, an actuating part mounted for oscillatory movement about the axis of the rock member and connected to said rod to be operated back and forth upon rotation of the crank-shaft, an actuated part actuated thereby to automatically move said control lever and said rock shaft to stop the press, spring means for normally urging one 90 95 of said parts into engaging position with the other part, the arrangement being such that initial movement of the control lever from the stopping position is first effective in causing the disengagement of the said 100 parts to permit the continued operation of the hand control lever for the engagement of the clutch and the release of the brake, said control mechanism having provision effective on one of said parts in preventing 105 its engagement with the other part to permit the continued operation of the press.

8. In a power press, a driving member, a crank-shaft, a clutch between said driving member and crank-shaft, a brake for stopping the rotation of the crank-shaft, a rock shaft for operating the clutch and brake, an actuating part connected to the crank-shaft to be responsive to the movements thereof, manual control mechanism comprising a hand operated control lever capable of manual operation at any time in the operation of the press to effect its manual starting and stopping and connected through a lost motion to the rock shaft, an actuated part adapted to be engaged and moved by said actuating part to automatically move said control lever and said rock shaft and stop the operation of the press, means for normally urging one of said parts into engaging position with the other part, said control mechanism having provision effective on one of said parts in preventing the engagement of the parts to permit the continued operation of the press while the hand 110 115 120 125 130

lever is held in the starting position, the arrangement being such that initial movement of the hand control lever from the stopping position is first effective in causing the disengagement of the said parts to permit the continued operation of the hand control lever for the engagement of the clutch and the release of the brake, and a manually adjustable disengaging device operable to prevent the engagement of the said parts to permit the continued operation of the press:

9. In a power press, a drive member, a crank-shaft, a clutch between said drive member and crank-shaft, a brake connected to stop the rotation of the crank-shaft, toggle levers for controlling the brake, a rock shaft connected to the clutch and to the brake toggle levers, a rock member mounted for oscillatory movement about said shaft axis, a rod connected to said rock member and reciprocally operable by said crank-shaft, a hand control lever capable of manual operation at any time in the operation of the press to effect the manual starting or stopping of the press, an intermediate control part fast on said shaft and connected

through a lost motion to the control lever, an actuating part provided on said rock member, an actuated part actuated thereby mounted to oscillate with the rock shaft about the rock shaft axis to automatically return said rock shaft to the stopped position, spring means for normally urging one of said parts into engaging relation with the other part, disengaging means manually adjustable to prevent the engagement of said parts to permit the continued operation of the press, and means for normally urging said hand control lever towards the stopped position, the arrangement being such that initial movement of the hand control lever from the stopped position is first effective in causing the disengagement of the actuating and actuated parts to permit the continued operation of the hand control lever for the engagement of the clutch and the release of the brake.

In testimony whereof I hereto affix my signature.

ARTHUR A. BYERLEIN.
